(57) **CLAIM**

The ornamental design for a seat belt grab hook as shown.

DESCRIPTION

FIG. 1 is a drawing showing a top plan view and the bottom plan view being a mirror image of my new design for a seat belt grab hook.

FIG. 2 is an enlarged perspective view rotated to show top, handle end, and partial left-side and right-side surfaces thereof;

FIG. 3 is an enlarged perspective view rotated to show top, hook end and partial left-side and right-side surfaces thereof;

FIG. 4 is an enlarged perspective view rotated to show top, handle end and partial right-side surfaces thereof; and,

FIG. 5 is an enlarged perspective view rotated to show bottom, handle end and partial left-side and right-side surfaces thereof.

1 Claim, 5 Drawing Sheets
